INVENTOR

UNITED STATES PATENT OFFICE.

ARTHUR B. BELLOW, OF PITTSBURG, PENNSYLVANIA.

CAR-BOLSTER.

SPECIFICATION forming part of Letters Patent No. 779,389, dated January 3, 1905.

Application filed May 2, 1902. Serial No. 105,635.

To all whom it may concern:

Be it known that I, ARTHUR B. BELLOW, of Pittsburgh, in the county of Allegheny and State of Pennsylvania, have invented a new and useful Car-Bolster, of which the following is a full, clear, and exact description, reference being had to the accompanying drawings, forming part of this specification, in which—

- 10 Figure 1 is a partial transverse section on the line II of Fig. 2 looking toward the left. Fig. 2 is an end elevation showing one form of my improved bolster in position, the side portions of the truck being broken away. Fig. 15 3 is a partial top plan view, and Fig. 4 is an end perspective view, of the bolster of Figs. 1 and 2. Fig. 5 is a partial side elevation, and Fig. 6 an end elevation, showing another form of bolster. Figs. 7 and 8 are views similar to Figs. 5 and 6, showing another form of the invention; and Figs. 9 and 10 are similar views showing a similar form, the fish-belly transom being inverted.

20 My invention relates to bolsters for railway trucks and cars, and is designed to provide a strong, light, and simple construction which can be easily and cheaply made from rolled Z-bars or pressed-up sections of transverse U shape.

30 In the drawings, referring to the form of Figs. 1 to 4, inclusive, I show the bolster as formed of two Z-bars 2, arranged parallel to each other, with their upper flanges 3 projecting inwardly. The outer lower flanges 4 of each Z-bar are notched near their ends, as shown at 5, and vertical angles 6 are riveted to the web in line with the notched portions to form guides.

40 In Figs. 1 and 2, 7 indicates the inverted arch-bar, 8 the spring-plank channel-iron, and 9 the coiled springs of the bolster. These springs bear at their upper ends upon the spring-bearing seat 10, which is secured between the webs of the Z-bars and fits against their upper 45 flanges. I have shown the seat as having lower depending flanges 11, and the securing-rivets which extend through the webs and the seat also preferably extend through the guiding angles 6. The bolster guide-bars 12 extend

vertically between the pairs of angles 6 on the outer sides of the Z-bars. The intermediate parts of the Z-bars are secured together by top plate 13, and I preferably use a lower reinforcing-plate 14 for the central part of the bolster. 15 represents the center plate. 55

In Figs. 5 and 6 I show a bolster of modified form wherein instead of using two Z-bars I form the body of a pressed or bent plate of inverted-trough form, having lower outwardly-projecting flanges 4'. In this form, 60 as in the previous one, these flanges are notched at 5', while the side portions 2' are provided with vertical guide-angles 6'. The spring-bearing seat 10' is the same as before, as are also the upper and lower middle 65 plates 13' and 14' and the center plate 15'. In this form I preferably reinforce the central portion of the bolster by means of pressed shapes 16, having flanges extending around them and riveted to the top and sides of the 70 trough. These fillers are preferably spaced an equal distance from the center of the bolster on each side.

In Figs. 7 and 8 I show a form similar to that of Figs. 1 to 4, inclusive, except that the 75 body of the bolster is of fish-belly form, being shallower at its end than at the center. In this case I preferably reinforce the shallow end portions by lower plates 17, riveted to the flanges 4", and forming a part of the 80 spring-bearing seat. In this case the Z-bars are preferably pressed up from steel sheets in order to obtain the fish-belly form. Fillers 18 are provided between the end portions and above the plates 17. 85

In Figs. 9 and 10 I show a form similar to that of Figs. 7 and 8, except that the fish-belly is inverted, the parts otherwise being the same as before.

The advantages of my invention result from 90 the use of the body formed either of two Z-bar members or of an inverted trough, since a light and strong construction is thus afforded, and also from the fish-belly form, which makes the construction lighter, while retaining strength 95 and distributing the metal according to the strains.

The construction may be used as a body-

bolster and many changes may be made in the form of the bolster and other parts without departing from my invention.

I claim—

- 5 1. A truck-bolster having a body with inwardly-projecting portions at the top, and lower outwardly-projecting flanges, said sides being free from other flanges, the lower outer flanges being cut away near the ends; substantially as described.
- 10 2. A bolster having a body with inwardly-projecting portions at the top and lower outwardly-projecting flanges, said sides being free from other flanges, the lower outer flanges being cut away near the ends, and guides above the cut-away flanged portions and consisting of angles riveted in pairs; substantially as described.
- 15 3. A truck-bolster of fish-belly form having outwardly-projecting lower flanges and being free from outwardly-projecting upper flanges, and lower reinforcing members se-

cured to the outer ends of the bolster; substantially as described.

4. A truck-bolster of fish-belly form having lower outwardly-projecting flanges cut away near the ends, and vertical guides secured above the cut-away portions; substantially as described.

5. A truck-bolster formed of two Z-shaped members with their lower outwardly-projecting flanges cut away near the outer ends, an inner reinforcing member at the end, and vertical guides above the cut-away flange portions secured by rivets extending through the inner reinforcing member; substantially as described.

In testimony whereof I have hereunto set my hand.

ARTHUR B. BELLows
